United States Patent Office

Des. 180,337
Patented May 21, 1957

180,337

SPECTACLE FRAME OR THE LIKE

Joseph J. Margules, Southbridge, Mass., assignor to American Optical Company, Southbridge, Mass., a voluntary association of Massachusetts

Application October 31, 1955, Serial No. 38,669

Term of patent 14 years

(Cl. D57—1)

Fig. 1

Fig. 2

Fig. 1 is a front elevational view of a spectacle frame embodying my new design; and

Fig. 2 is a top plan view thereof, with the ends of the temples broken off for convenience of illustration.

The characteristic features of my new design are shown in full lines in the drawing.

I claim:

The ornamental design for a spectacle frame or the like, substantially as shown and described.
